UNITED STATES PATENT OFFICE.

ANDREW L. TURNER, OF KIEFER, OKLAHOMA.

DIMMER.

Application filed July 30, 1923. Serial No. 654,656.

To all whom it may concern:

Be it known that I, ANDREW L. TURNER, a citizen of the United States, residing at Kiefer, in the county of Creek and State of Oklahoma, have invented certain new and useful Improvements in Dimmers, of which the following is a specification, reference being had to the accompanying drawings.

This invention relates to certain improvements in dimmers and it is an object of the invention to provide a novel and improved device of this general character which operates effectively to cut out the intensified or far reaching light rays so that the driver of an approaching car will not be blinded yet at the same time permitting the headlight to effectively illuminate the advance of the vehicle upon which it is mounted.

The invention consists in the details of construction and in the combination and arrangement of the several parts of my improved dimmer whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a dimmer constructed in accordance with an embodiment of my invention and in applied position;

Figure 2 is an elevational view of the device as illustrated in Figure 1;

Figure 3 is a view similar to Figure 2 showing the shield in raised position;

Figure 4 is a sectional view taken substantially on the line 4—4 of Figure 1;

Figure 5 is a fragmentary view partly in section and partly in elevation illustrating in detail the mounting of the shield and the parts concomitant thereto.

As disclosed in the accompanying drawings, C denotes a headlight casing of a conventional type and which has arranged therein at the axial center thereof the illuminating member or lamp L.

Secured within the casing C at the lower portion thereof is an upstanding post 1 of predetermined height and which has rotatably supported thereto a shaft 2, said

shaft being disposed in the same general direction as the axis of the headlight C and substantially in parallelism therewith. Secured to the outer portion of the shaft 2 is an opaque shield 3 of celluloid or other suitable material, said shield being green, blue or of any desired color.

The shaft 2 inwardly or rearwardly of the post 1 has threaded thereon a pinion 4, said pinion being effectively maintained in applied position by the binding nuts 5 mounted upon the shaft 2 and in contact with the opposite sides of the pinion 4.

The pinion 4 meshes with an arcuate rack 6 carried by an elongated member 7. The member 7 at its central part is provided with an arm 8 disposed in a direction away from the rack 6 and having its outer end portion pivotally connected as at 9 with the post 1 preferably to one side of the shaft 2.

One end portion of the member 7 has engaged therewith an extremity of a retractile member or coil spring 10, the opposite end portion of which being secured by the holding bolt 11 to the post 1.

The post 1 is provided with a foot 12 which has close contact with the reflector 14 arranged within the casing C and the bolt 11 passes through said foot 12 and reflector 14 and is maintained in applied position by the nut 15. The bolt 11 is tubular and has disposed therethrough the flexible member 16 which is secured to the opposite end of the member 7. This member 16 is continued through the wall proper of the casing and through a suitable guide tube 17, terminating in a button or head 18 which is so positioned as to be readily accessible to the driver of the car.

Normally the retractile member or spring 10 maintains the shield 3 in its lowermost position or below the member or lamp L. Upon imposing pull upon the flexible member 16 the shield 3 will swing upwardly and directly in advance of the member or lamp L whereby the direct or straightest light rays will be obstructed yet permitting sufficient illumination in advance of the vehicle to which the casing C is applied and yet preventing blinding of the driver of an approaching vehicle.

The post 1 is of a length to terminate below the member or lamp L so that when the shield 3 is in its lowemost or inoperative position no undue obstruction is offered to the rays emitted from the casing.

From the foregoing description it is thought to be obvious that a dimmer constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a lamp casing and an illuminating member positioned therein, an upstanding post supported by the casing and positioned therein, a shaft rotatably supported by the upper portion of the post, an elongated member supported by the upper portion of the post for rocking movement, said member being provided with an arcuate rack, a pinion fixed to the shaft and meshing with the rack, a spring operatively engaged with one end portion of the member for automatically moving the member in one direction, manual means operatively engaged with the opposite end portion of the member for imparting movement thereto in the opposite direction, and an opaque shield
2. In combination with a lamp casing and an illuminating member positioned therein, an upstanding post supported by the casing and positioned therein, said post being provided with a foot, a tubular bolt coaxing with said foot and a wall of the casing for holding the post in applied position, a shaft rotatably supported by the post, a shield fixed to the shaft, said shield when in one position being directly in advance of the illuminating member and when in lowered position being positioned below said illuminating member, an elongated member supported by the post for rocking movement, said member being provided with an arcuate rack operatively engaged with the shaft, automatic means coaxing with said member for rotating the shaft in a direction to maintain the shield in its lowered position, a flexible member secured to the member, and extending exteriorly of the casing through the tubular bolt, said flexible member providing means to manually move said member to adjust the shield to its raised position.

In testimony whereof I hereunto affix my signature.

ANDREW L. TURNER.

carried by the shaft, said shield when in one position being directly in advance of the illuminating member and when in a second position being below the illuminating member.

2. In combination with a lamp casing and an illuminating member positioned therein, an upstanding post supported by the casing and positioned therein, said post being provided with a foot, a tubular bolt coaxing with said foot and a wall of the casing for holding the post in applied position, a shaft rotatably supported by the post, a shield fixed to the shaft, said shield when in one position being directly in advance of the illuminating member and when in lowered position being positioned below said illuminating member, an elongated member supported by the post for rocking movement, said member being provided with an arcuate rack operatively engaged with the shaft, automatic means coaxing with said member for rotating the shaft in a direction to maintain the shield in its lowered position, a flexible member secured to the member, and extending exteriorly of the casing through the tubular bolt, said flexible member providing means to manually move said member to adjust the shield to its raised position.
